United States Patent Office.

IMPROVED WINDOW-BLIND FASTENING.

J. LUTHER AND A. MARSH, OF WORCESTER, MASSACHUSETTS.

Letters Patent No. 60,210, dated December 4, 1866.

SPECIFICATION.

KNOW ALL MEN BY THESE PRESENTS:

That we, J. LUTHER and A. MARSH, both of the city and county of Worcester, and Commonwealth of Massachusetts, have invented certain new and useful improvements in Window-Blind Fastenings; and we do hereby declare that the following is a full, clear, and exact description of the same, reference being had to the accompanying drawings, forming a part of this specification, in which—

Figure 1 represents a perspective view of a part of a blind, with our fastening applied thereto.

Figure 2 represents a bottom view of our blind fastening.

Figure 3 represents a section on line A B, fig. 2.

Figure 4 represents a side view of the fastening spring looking in the direction of the arrow, fig. 5; and

Figure 5 represents a section on line C D, fig. 4.

To enable those skilled in the art to which our invention belongs to make and use the same, we will proceed to describe it.

In the drawings, A represents the base or main piece of the fastening, which is fastened to the under side of the blind by two screws, *a* and *b*. The parts *c c* of A are depressed down the width of spring C from the back part of A, while a hub *d* rises up even with the back part of A to support the head of screw *a*, as shown in fig. 3. A curved recess is made in the part A, back of the screw *a*, to receive the curved part *e* of spring C, so that when the spring C is once placed in position, as shown in fig. 2, and screw *a* inserted as shown in figs. 2 and 3, the spring C is securely held in place without any other fastening, while the curved ends D D of spring C are free to work or spring back and forth on or over the depressed parts *c c*, as indicated in red lines, fig. 2. The ends of the parts *c c* are blunt, cut or curved out, as seen at 1, so as to afford a proper point of resistance to receive the pin *f* and arrest the motion of the blind in the operation of opening or shutting the same, and that, too, without injury to the spring C. The curves *g g* of spring C, in connection with the curved ends E E of part A, operate to hold the blind, when once open or shut, until sufficient force is applied to the blind to throw back the end D of spring C, as shown in red lines, fig. 2. When the device is applied to a blind, one end of the spring answers the purpose of holding the blind open, while the other end answers the purpose of holding it when closed. The device is simple, and not liable to get out of order. *f* represents a pin in the window-sill, which is clasped between spring C and the end E, as shown in black lines, fig. 2. A staple or some other suitable device is to be attached to the side of the building for a similar purpose when the blind is open.

Having described our improved blind fastening, what we claim therein as new, and of our invention, and desire to secure by Letters Patent, is—

1. The peculiar formation of spring C, as shown, and for the purposes stated.
2. Making a blind fastening of two pieces, a spring and main or bed-piece, when the latter is constructed as described, so that it will receive and arrest the blind when opening or closing the same, without injury to the spring.
3. The combination, with the main or bed-piece A, and spring C, of screw *a*, as shown and described, whereby the screw serves to hold the spring in place, and also answers as a fastening to the blind.

J. LUTHER,
A. MARSH.
